United States Patent Office

Des. 190,931
Patented July 18, 1961

190,931

BOTTLE

Martin J. Ferguson, Rye Colony, Rye, N.Y.

Filed Apr. 2, 1959, Ser. No. 55,312

Term of patent 14 years

(Cl. D58—8)

FIG. 1 is a front elevational view of a bottle embodying my new design;

FIG. 2 is a side elevational view of the same; and

FIG. 3 is a perspective view of the same.

I claim:

The ornamental design for a bottle, as shown.
